DELIVERY DEVICE

Charles H. Biggs, Lewisburg, Tenn.

Application May 14, 1941, Serial No. 393,454

9 Claims. (Cl. 258—3)

This invention relates to a novel device for delivering train orders and despatches to fast moving trains, and more particularly to a device adapted to be held by a station employee so that a member of the crew of a fast moving train may pass his arm through a portion of the device and detach said portion from the remainder of the device for obtaining a despatch attached to the detachable portion of the delivery device.

More particularly, it is an aim of the invention to provide a despatch delivery device which is so constructed that it can be easily engaged by a member of the crew of a fast moving train without danger of striking any part of the device which is not detachable to avoid danger of injury to either the man holding the device or the man to receive the despatch therefrom.

Another aim of the invention is to provide a despatch delivery device wherein the portion of the device carrying the despatch which is to be detached and which is engaged by the arm of a member of the train crew is arranged to project away from the portion which is retained by the station employee to afford a large opening through which the arm of the crewman can be inserted to insure delivery of the device and to practically eliminate any danger of the despatch being missed.

Still another aim of the invention is to provide a despatch delivery device to which a despatch may be quickly and easily attached, and in which the detachable portion of the delivery device may be quickly and easily applied to the portion held by the station agent and which supports the detachable portion.

Other objects and advantages of the invention will hereinafter become more fully apparent from the following description of the drawing, which illustrates a preferred embodiment of the invention, and wherein:

Figure 1 is a front elevational view, partly in section, of the delivery device,

Figure 2 is a side or edge view in elevation of the same,

Figure 3 is an enlarged longitudinal sectional view taken substantially along the plane of the line 3—3 of Figure 2, and

Figure 4 is an enlarged cross sectional view of a portion of the delivery device, taken substantially along a plane indicated by the line 4—4 of Figure 1.

Referring more particularly to the drawing, wherein like reference characters designate like or corresponding parts throughout the different views, 10 designates the despatch delivery device

in its entirety, and which includes a Y-shaped socket member, designated generally 11, having corresponding diverging socket portions 12, and a socket portion 13, which is disposed between the socket portions 12 and which projects and opens in a direction away from said socket portions. A pair of rods or arms 14 have corresponding ends disposed in the sockets 12 and secured thereto by fastenings 15. The arms 14

10 project outwardly from one another in diverging relationship to form the prongs of a fork, designated generally 16. An elongated handle 17 has one end secured in the socket 13 by fastenings 15, and projects therefrom in a direction away from

15 the arms 14.

A sleeve 18 is mounted on the opposite end of each of the arms or rods 14, and is attached thereto by fastenings 15. The sleeves 18 have angularly disposed free ends forming sockets 19, which sockets are substantially parallel to one another.

An elongated strip 20 is provided with ends 21 which are adapted to loosely engage in the sockets 19, as best seen in Figure 3. The strip 20 is formed of any suitable resilient material such as spring steel or wood, and is provided adjacent its ends 21 with eyelets 22, as best seen in Figure 3. The strip 20 between the eyelets 22 and the ends 21, is provided with collars or shoulder members 23, which abut against the outer ends of the sockets 19, to limit the inward movement of the ends of the strip 20 relatively to the sockets 19, as seen in Figure 3.

A conventional spring clip 24 is attached to one side of the inner end of the socket 13 and between the inner ends of the sockets 12, as best seen in Figure 1. The spring clip 24 is connected at one end to the socket 13 and has a rounded opposite end which yieldably engages against the socket 13. A flexible member, such as cord, 25 is secured at its ends, as seen in Figure 3, to the eyelets 22, and has its intermediate portion releasably held by the spring clip 24 taut so that the cord 25 will retain the ends 21 in engagement with the sockets 19 to detachably mount the strip 20 in an outwardly bowed relationship relatively to the fork 16, as illustrated in Figure 1.

A conventional spring clip 26 is attached to the outer side of the intermediate portion of the strip 20 and is adapted to detachably engage an article, as indicated at 27, in dotted lines in Figure 1, such as a train order or despatch, waybill or the like. A supporting member, designated generally 28, and best seen in Figure 4, includes two spring clips 29 and 30, which are attached

in end to end relationship relatively to one another by means of a fastening 31 which extends through the intermediate portions of the clips 29 and 30. Clip 29 is adapted to detachably engage the socket 13, below the clip 24, and the clip 30 is adapted to detachably engage a conventional flashlight 32, as seen in dotted lines in Figure 1, for mounting the flashlight on the device 10.

With the parts assembled, as seen in Figure 1, the strip 20 and the cord 25 combine to form a relatively large opening, the larger portion of which is beyond the outer end of the fork 16, and the remainder of which is within the fork. The delivery device 10 is adapted to be held by station employees by the handle 17 so that the fork 16 projects upwardly and outwardly from the man holding the delivery device 10 so that a member of the crew of a fast moving train can readily pass his arm into the opening formed by the strip 20 and the cord 25, and the pull exerted on the strip 20 by the arm of the trainman will cause the cord 25 to become readily released from the clip 24 so that the detachable parts 20 and 25 may be readily removed from the fork 16 by the trainman. The article 27 can then be removed from the clip 26 and the parts 20 and 25 dropped from the train to be retrieved by the station agent or employee. When the delivery device 10 is used at night, the flashlight 32 is employed to illuminate the strip 20 and the cord 25, so that a trainman will have no difficulty in inserting his arm into the opening formed by these parts, and the opening thus formed is sufficiently large so that there will be slight chance of a trainman missing the opening with his arm so that the despatch will be invariably picked up by the trainman regardless of the speed at which the train may be moving.

Various modifications and changes are contemplated and may obviously be resorted to as only a preferred embodiment of the invention has been disclosed.

I claim as my invention:

1. A delivery device comprising a fork, said fork having diverging prongs, sockets formed in the remote ends of said prongs, a bow having its ends loosely disposed in said sockets, a cord attached at its ends to said bow, adjacent its ends, and a spring clip mounted on the fork for detachably engaging the intermediate portion of the cord for retaining the ends of the bow in engagement with said sockets.

2. A delivery device as in claim 1, comprising a spring clip attached to the intermediate portion of the bow and adapted to detachably en-

gage an article to be supported by the delivery device.

3. A delivery device as in claim 1, said bow comprising an elongated strip of resilient material.

4. A delivery device as in claim 1, said fork including an elongated handle projecting from the apex of the prongs and in a direction away from the prongs.

10 5. A delivery device as in claim 1, comprising a resilient support composed of oppositely projecting pairs of spring jaws, one of said pairs of spring jaws being detachably connected to the fork, adjacent its apex, the other pair of spring jaws being adapted to engage and detachably mount a flashlight for supporting the flashlight in a position to illuminate the opening in the delivery device formed by the prongs and the bow.

6. A delivery device as in claim 1, said fork 20 including a Y-shaped socket having corresponding diverging socket portions for engaging the adjacent ends of the prongs, and a handle having one end secured in and projecting from the other socket portion of said Y-shaped socket 25 member.

7. A delivery device comprising a fork having diverging arms, said arms being provided with substantially parallel sockets at their free ends, an elongated resilient strip having its ends 30 30 movably mounted in said sockets and supported thereby in outwardly bowed relationship relatively to the fork, and an article holding member connected to the intermediate portion of said strip.

35 8. A delivery device as in claim 7, comprising a flexible element connected at its ends to said strip, adjacent the ends thereof, and a spring clip carried by the fork for detachably engaging the intermediate portion of said flexible strip to hold the flexible member taut so that the flexible member will retain the ends of the resilient strip in engagement with said sockets.

9. A delivery device as in claim 7, comprising a flexible element connected at its ends to said 45 strip, adjacent the ends thereof, a spring clip carried by the fork for detachably engaging the intermediate portion of said flexible strip to hold the flexible member taut so that the flexible member will retain the ends of the resilient strip 50 in engagement with said sockets, the ends of said strip being loosely mounted in said sockets, and said strip being provided with shoulder members adjacent its ends for engaging the outer ends of said sockets.

CHARLES H. BIGGS.
